UNITED STATES PATENT OFFICE

CHARLES E. WEHN, OF ALAMEDA, CALIFORNIA, ASSIGNOR TO LISTO PENCIL CORPORATION, OF ALAMEDA, CALIFORNIA, A CORPORATION OF CALIFORNIA

PENCIL

Application filed February 19, 1929. Serial No. 341,217.

This invention relates to mechanical pencils.

The object of the present invention is to generally improve and simplify the construction and operation of pencils of the character described; to provide a structure which permits reduction in the number of parts employed; to provide a structure which permits material reduction in the over all length, and furthermore, to provide a structure which will be rigid and substantial and easy to operate.

The pencil is shown by way of illustration in the accompanying drawings in which:

- 15 Fig. 1 is an exterior view of the pencil,
Fig. 2 is a central longitudinal section,
Fig. 3 is a view of the slotted tube, together
with a portion of the mechanism carried
thereby,
20 Fig. 4 is a side elevation of the lead ejector.
Referring to the drawings in detail, particularly Fig. 3, A indicates in general a tube constructed of a suitable material, such as brass or the like. One end of the tube is provided with a longitudinal slot through its wall and extending substantially half the length of the tube, such as shown at 2 which functions as a guide for a lead pusher which is slidable within the tube and is generally indicated at 3. The other end of the tube indicated at 4, serves the function of receiving and securing the pencil lead indicated at 5. The forward end of the tube is provided with a split point 6, to frictionally retain the lead. The point is provided with a shoulder 7 and this secures a pencil point or head 8, as will hereinafter be described. The opposite end of the tube is closed by a cap 9, which is soldered, pinned or otherwise secured as at 10. An exteriorly threaded sleeve 11 is slidably mounted on the tube and this sleeve is perforated, as indicated at 12 to receive the anchor end 13 of the lead pusher, indicated at 3.

45 A collar 14 is secured on the tube, and a sleeve 15 is journalled on the tube to freely rotate, this sleeve being interposed between the collar 14 and the head 8 of the pencil.

By referring to Figs. 1 and 2 it will be noted that the tube A, the end cap 9, the

sleeve 11, the collar 14 and the sleeve 15 are all enclosed by means of an exterior tube or barrel section 16. This tube is secured to the sleeve 15 by pins 17, or otherwise and as the sleeve is freely rotatable on the tube A barrel 16 will also be free to rotate. The barrel 16 is interiorly threaded, as shown at 18, the threads engaging the threads of the sleeve 11 so that when the barrel 16 is rotated the sleeve will be advanced or retracted, as will hereinafter be described.

The barrel 16 serves several functions, to wit, that of enclosing a main mechanism, secondly that of advancing or retracting the sleeve 11, third that of forming a spare lead receiving chamber which is indicated at 19, and fourth, that of supporting an end closure cap 20 and an eraser 21.

In actual operation, when the pencil is being constructed and assembled, the point or head 8 is first slipped over the end of the tube A, until it assumes the dotted line position shown in Fig. 3. It is here secured against the shoulder 7 of the point 6, either by being pressed on or by being cemented. When the head is in position sleeve 15 is applied, collar 14 is next applied and secured either by pinning it to the tube A, soldering or otherwise, care being taken however that sleeve 15 will be permitted to freely rotate.

The lead pusher is next inserted in the grooved portion 2 and the sleeve 11 applied. Cap 9 is then placed in position and pinned or otherwise secured. This completes the assembling of the main operating part of the mechanism, and this assembly is clearly shown in Fig. 3.

After this assembly has been completed, it is only necessary to apply the exterior barrel 16. This is screwed over the sleeve, and when the forward end of the tube is passed over the sleeve 15 and abuts the head 8 it is secured by pins 17 or the like. The assembling of the pencil is then completed, when the eraser and the closure cap 20 are applied.

The cap 9 on the end of the tube A serves two functions, first that of limiting movement of the sleeve 11 longitudinally of the tube, and secondly it functions as a bottom section for the lead receiving chamber 19.

while the eraser forms a closure for the opposite end of the lead receiving chamber. If the pencil is empty and it is desired to load the same, cap 20 and eraser 21 will be removed so that one of the pencil leads may be taken out. After the lead is taken out, the eraser and cap are replaced and the barrel 16 is rotated until sleeve 11 engages the cap 9. When the sleeve assumes this position pusher 3 is completely retracted and the lead may thus be inserted in the point end, as indicated at 5. Reverse rotation of the barrel will feed the lead pusher 3 forwardly, and thus advance the lead as required.

15 It should also be noted that the mechanism disclosed in this application permits a material reduction in the over-all length of pencils of this character. The present structure also permits the formation of a lead receiving chamber such as shown at 19. That may, of course, be entirely eliminated if desired, thus further reducing the length of the pencil.

25 It should also be noted that the barrel 16 is supported at two points, first at its forward end where it is secured to the sleeve 15, and secondly at a point intermediate its ends, to wit by the cap 9. The structure is thus rigid and substantial, and it is at the same time easy to operate as the sleeve 11 and the pusher 3 may be advanced or retracted either by rotation of the head 8 or the barrel 16.

35 While certain features of the present invention are more or less specifically described, I wish it understood that various changes may be resorted to within the scope of the appended claims, similarly, that the materials and finishes of the several parts employed may be such as the manufacturer may decide, or varying conditions or uses may demand.

Having thus described my invention, what I claim and desire to secure by Letters Patent is:

45 1. A pencil of the character described comprising a tube slotted at one end and having a central passage formed therethrough in communication with the slot, said central passage forming a receptacle for a pencil lead, an exteriorly threaded sleeve slidably mounted on the tube, a pusher rod lying in the central passage having a lateral extension extending through the slot, means connecting the pusher rod and the sleeve, said means securing the sleeve and pusher rod against rotation, a head member secured on the tube, a collar secured on the tube and spaced from the head member, a second sleeve rotatable on the tube and interposed between the head member and the collar, a tubular barrel enclosing the rotatable sleeve, the collar, the first-named sleeve, the tube and the pusher rod, one end of the barrel abutting the head member, means securing the abutting end of the barrel to the rotatable sleeve, threads formed on the inner surface of the barrel and engaging the nut, whereby rotation of the barrel and the sleeve about the tube will impart longitudinal movement to the nut and the pusher rod, a cap secured on the inner end of the tube, said cap together with the collar limiting longitudinal movement of the nut and the pusher rod with relation to the tube, a lead receiving chamber formed in the tubular

formed on the inner surface of the barrel and engaging the first-named sleeve, whereby rotation of the barrel and the sleeve about the tube will impart longitudinal movement to the nut and the pusher rod.

2. A pencil of the character described comprising a tube slotted at one end and having a central passage formed therethrough in communication with the slot, said central passage forming an exteriorly threaded receptacle for a pencil lead, a sleeve slidably mounted on the tube, a pusher rod lying in the central passage having a lateral extension extending through the slot, means connecting the pusher rod and the sleeve, said means securing the sleeve and pusher rod against rotation, a head member secured on the tube, a collar secured on the tube and spaced from the head member, a second sleeve rotatable on the tube and interposed between the head member and the collar, a tubular barrel enclosing the rotatable sleeve, the collar, the first-named sleeve, the tube and the pusher rod, one end of the barrel abutting the head member, means securing the abutting end of the barrel to the rotatable sleeve, threads formed on the inner surface of the barrel and engaging the nut, whereby rotation of the barrel and the sleeve about the tube will impart longitudinal movement to the first-named sleeve and the pusher rod, and a cap secured on the inner end of the tube, said cap together with the collar limiting longitudinal movement of the first-named sleeve and the pusher rod with relation to the tube.

3. A pencil of the character described comprising a tube slotted at one end and having a central passage formed therethrough in communication with the groove, said central passage forming an exteriorly threaded receptacle for a pencil lead, a sleeve slidably mounted on the tube, a pusher rod lying in the central passage having a lateral extension extending through the slot, means connecting the pusher rod and said sleeve, said means securing the sleeve and pusher rod against rotation, a head member secured on the tube, a collar secured on the tube and spaced from the head member, a second sleeve rotatable on the tube and interposed between the head member and the collar, a tubular barrel enclosing the rotatable sleeve, the collar, the nut, the tube and the pusher rod, one end of the barrel abutting the head member, means securing the abutting end of the barrel to the rotatable sleeve, threads formed on the inner surface of the barrel and engaging the nut, whereby rotation of the barrel and the sleeve about the tube will impart longitudinal movement to the nut and the pusher rod, a cap secured on the inner end of the tube, said cap together with the collar limiting longitudinal movement of the nut and the pusher rod with relation to the tube, a lead receiving chamber formed in the tubular

barrel and a closure for said lead receiving chamber.

4. A lead controlling mechanism for a pencil of the character described, comprising a tube adapted to contain a lead, a split tip formed integrally with said tube for frictionally retaining the lead, a head member secured to the tube, a sleeve rotatably mounted on the tube adjacent the head member, said sleeve being adapted to support a rotatable pencil barrel, a collar adjacent said sleeve and fastened to said tube whereby longitudinal movement of the sleeve upon the tube is prevented, and means whereby rotation of the barrel with relation to said head member will cause the lead to be pushed outwardly from the tube.

5. A lead feeding mechanism for a pencil of the character described comprising a tube adapted to contain a lead and having a longitudinally extending slot formed therein, said slot extending inwardly from one end substantially half the length of the tube, a push rod slidably carried by the tube and having a lateral extension extending through the slot, an exteriorly threaded sleeve slidably mounted on the tube and connected to said lateral extension, a collar secured to the tube and adjacent the inner end of said slot, and a cap secured on one end of the tube, said collar and cap being adapted to limit the longitudinal movement of the sleeve upon the tube.

6. A lead controlling mechanism for a pencil of the character described comprising a tube adapted to contain a lead, a head member secured to the tube, a sleeve rotatably mounted on the tube adjacent the head member, said sleeve being adapted to support a rotatable pencil barrel, a collar on the tube adjacent the sleeve whereby longitudinal movement of the sleeve upon the tube is prevented, and means whereby rotation of the barrel and sleeve with relation to the head member will cause the lead to be pushed outwardly from the tube.

CHARLES E. WEHN.
